Attorney.*

UNITED STATES PATENT OFFICE.

JAMES A. SHERMAN, OF BUFFALO, NEW YORK.

CAST CHILLED REAMER.

SPECIFICATION forming part of Letters Patent No. 399,349, dated March 12, 1889.

Application filed January 2, 1889. Serial No. 295,130. (No model.)

To all whom it may concern:

Be it known that I, JAMES A. SHERMAN, of Buffalo, in the county of Erie and State of New York, have invented certain new and useful Improvements in Cast-Iron Chilled Reamers; and I do hereby declare that the following description of my said invention, taken in connection with the accompanying sheet of drawings, forms a full, clear, and exact specification, which will enable others skilled in the art to which it appertains to make and use the same.

This invention has general reference to improvements in cast-iron reamers for boring car-wheels, &c.; and it consists, essentially, in the method of producing the same, as hereinafter first fully set forth and described, and then pointed out in the claims.

In the drawings already referred to, which serve to illustrate my said invention more fully, Figure 1 is an elevation of a reamer constructed in accordance with my invention. Fig. 2 is a bottom plan and Fig. 3 a top view of the same. Fig. 4 is a longitudinal sectional elevation in line x x of Fig. 3.

Like parts are designated by corresponding letters of reference in all the figures.

The object of my invention is the production of a cheap reamer especially designed for use in boring-machines for boring the hubs of car-wheels, but also applicable for all other purposes where a reamer can be employed. To attain the result described, I produce these reamers of all the various sizes in the process of casting in so-called "chills" of iron of a very close grain, whereby I at once obtain the correct shape of the tool and at the same time the requisite hardness to accomplish the object in view, so that when the cutting-edges of the reamer are trued up by first revolving the reamer upon a suitable mandrel in a machine adapted for such purpose, and then grinding the cutting-faces by means of an emery-wheel to the correct diameter, and finally relieving the same to give the necessary rake or clearance, I produce an article

which for cheapness of cost cannot be excelled by any other method of construction, while for durability it will compare favorably with reamers of the best tool or crucible steel. 50 In casting these reamers I prefer to form the body A with a taper aperture, B, and to arrange recesses C in the upper face, said recesses serving as drivers in conjunction with a suitable mandrel. (Not shown.) I also prefer to "round off" the cutting-points D, as shown in Figs. 1, 2, and 4, and to so grind them that all the cutting-points will act simultaneously. I have used these reamers for some time for boring the hubs of chilled car-wheels, and find them to answer all the purposes and requirements of such work as well as any, while I have been able to produce them at a cost less than what the steel of a reamer as now made would cost. 60

Having thus fully described my invention, I claim as new and desire to secure to me by Letters Patent of the United States—

1. As an improved article of manufacture, a cast-iron chilled reamer for iron working 70 having a body provided with longitudinally-projecting cutting-teeth the edges of which are ground sharp along the advance edges and the bottom thereof, an interior bore, and recesses in its face, as and for the purpose set 75 forth.

2. The cast-iron chilled reamer hereinbefore described, consisting of the body A, having the taper bore B, the oppositely-located recesses C in the face of said body, and the laterally-projecting cutting-lips D, the latter being provided with the rounded cutting-edges E, relieved in the manner as and for the purpose set forth.

In testimony that I claim the foregoing as 85 my invention I have hereto set my hand in the presence of two subscribing witnesses.

JAS. A. SHERMAN.
